FIG. 3.

FIG. 4.

FIG. 5.

FIG. 6.

FIGURE 1 is a perspective view of a disposable anesthetist's kit showing our new design;

FIGURE 2 is a side elevational view of the filter and mask components, respectively;

FIGURE 3 is a top plan view of the filter and mask components, respectively;

FIGURE 4 is a rear elevational view of the filter and mask components, respectively;

FIGURE 5 is a front elevational view of the mask and filter components, respectively; and,

FIGURE 6 is a bottom plan view of the filter and mask components, respectively.

This is a continuation-in-part of design application Ser. No. 14,323, filed Nov. 5, 1968.

We claim:

The ornamental design for a disposable anesthetist's kit, substantially as shown.
